UNITED STATES PATENT OFFICE

168,259

BLOUSE OR SIMILAR ARTICLE

Tom C. Giangrosso, Long Hill, Conn.

Application May 9, 1952, Serial No. 19,646

Term of patent 3½ years

(Cl. D3—25)

To all whom it may concern:

Be it known that I, Tom C. Giangrosso, a citizen of the United States of America, residing in Long Hill, county of Fairfield, and State of Connecticut, have invented a new, original, and ornamental Design for a Blouse or Similar Article, of which the following is a specification, reference being had to the accompanying drawing, forming part thereof, wherein,

I claim:

The ornamental design for a blouse or similar article, substantially as shown.

TOM C. GIANGROSSO.
